(57) **CLAIM**

The ornamental design for a vehicle grille frame, as shown and described.

DESCRIPTION

FIG. 1 is a front elevational view of a vehicle grille frame, showing our new design.

FIG. 2 is a top perspective view thereof with an environmental grille mesh shown in FIG. 1 removed for clarity.

FIG. 3 is a bottom isometric view thereof.

FIG. 4 is a front elevational view thereof.

FIG. 5 is a rear elevational view thereof.

FIG. 6 is a left side elevational view thereof.

FIG. 7 is a right side elevational view thereof.

FIG. 8 is a top plan view thereof; and,

FIG. 9 is a bottom plan view thereof.

Stippling in the drawings represents the three-dimensional contours of the design, and is not intended to indicate surface decoration. The broken lines shown in the drawings depict portions of the vehicle grille frame or environment that form no part of the claimed design. The dash-dot broken lines define the boundaries of the claim and form no part of the claimed design.
